UNITED STATES PATENT OFFICE.

FRANK J. KROGMANN, OF EUREKA, CALIFORNIA.

DISPENSING CAN OR RECEPTACLE.

1,376,103.

Specification of Letters Patent. Patented Apr. 26, 1921.

Application filed March 16, 1920. Serial No. 366,289.

To all whom it may concern:

Be it known that I, FRANK J. KROGMANN, citizen of United States, residing at Eureka, in the county of Humboldt and State of California, have invented certain new and useful Improvements in Dispensing Cans or Receptacles, of which the following is a specification, reference being had therein to the accompanying drawings.

10 This invention relates to a dispensing can or receptacle and particularly to the construction of a can for the dispensing of liquid or oil.

15 The object of the invention is the construction of a receptacle or can which can be easily filled or emptied, without injury to the can, and which can will be susceptible of discharging the contents thereof from at least two of its sides.

20 With this and other objects in view, my invention comprises certain novel combinations, constructions and arrangement of parts as will be hereinafter fully described, illustrated in the accompanying drawing, 25 and more particularly pointed out in the appended claim.

In the drawing:

Figure 1 is a fragmentary view of a receptacle or can constructed in accordance 30 with the present invention.

Fig. 2 is a sectional view taken on line 2—2, Fig. 1.

Fig. 3 is a top plan view of the can shown in Fig. 1 with the spout turned over the 35 top of the can.

Fig. 4 is a view similar to Fig. 2, of another embodiment of the present invention.

Fig. 5 is a fragmentary plan view of the top of the can, showing the openings or 40 apertures therein.

Referring to the drawing by numerals:

From the following description, it will be understood that the oil contained in my can can be discharged without puncturing 45 the can for producing a vent. Further, the funnel-shaped spout 1 is movable and can be placed in different positions such as shown in Figs. 1 and 3. The can can be quickly refilled by removing the cap 2; the 50 stream of oil can also be limited to suit the demands of the person drawing the oil from the can; the can can be "opened" and "closed" without the use of any tools whatever. Now, in carrying out my invention, 55 the body 3 is provided with a top 4, which top 4 is provided with the usual handle 5.

Contiguous to the edge of the top, and preferably at one corner of the body, I place a sleeve 6 in the top, this sleeve being externally threaded upon its outer end, that projects above the top 4, and is smooth upon its inner end, which projects below the top (Figs. 2 and 4). Contiguous to the sleeve, I form an elongated aperture 7 in the top, which is a vent aperture, and this aperture communicates with a hollow tubing 8; this tubing 8 is preferably wider at its inner end and is secured partly to the side of the sleeve 6 (Fig. 2) and terminates short at 9 so as to allow the aperture 7 to 70 communicate with the interior of the tubing; the tubing or pipe tapers throughout its length and terminates at its outer end near the inner face of the body, at the side farthest from the side contiguous to the 75 sleeve 6, so that when the receptacle or can is turned downward or tilted for discharging the liquid through the sleeve 6 and spout 1, first slightly loosening the cap 2, air will pass through the vent opening 7 80 into the tubing 8 and thence into the receptacle or can. The tubing 8 is anchored at its inner end to the top 4 and the sleeve 6, by being secured thereto, as hereinbefore stated, and spaced away from the top 4 so as 85 to place the inner end of the tubing somewhat toward the middle of the body 3 for increasing the efficiency of the device by allowance of the greatest freedom to the entrance of air into the body. 90

In the embodiment shown in Fig. 4, the tubing 8^a is integral with the top 4 but substantially the same function of the free entrance of the air is accomplished by elongating the end 8^b to permit the ready passage of the air into the body of the receptacle or can. 95

The cap 2 is outwardly flared at its lower end 10, and fastened by rivets 11 to the inner face of the flared end 10 is a rubber disk or wide flat washer 12; the inner edge of this washer engages the threads on the sleeve 6. Fastened within the cap 2 at its lower end is an internally threaded sleeve 13, which sleeve bears at its lower end against the 100 inner face of the wide rubber disk or washer 12. 105

By slightly unscrewing the cap 2, air will be permitted to enter the vent opening 7, without permitting the liquid contained in 110 the body 3 to escape except only through the sleeve 6 and the spout.

By turning the spout 1 to one side of the body, oil can be discharged at that side, or turning the spout to the other contiguous side, oil can be discharged from this last-
5 mentioned side, so that oil can be discharged from different sides of the can, or by turning the spout over the top of the can as shown in Fig. 5, the spout will not be hit by foreign objects and injured. By removing the cap 2
10 and its spout 1, the can can be easily filled through the sleeve 6.

While I have described the preferred embodiments of my invention and have illustrated the same in the accompanying drawings, certain minor changes or alterations may appear to one skilled in the art to which this invention relates, in manufacturing the device on a large scale, and I therefore reserve the right to make such changes or alterations as will fairly fall within the scope of the appended claim.

What I claim is:

In a device of the class described, the combination with a body provided with a top, of a sleeve carried by said top, said top provided with a vent opening near the sleeve, a cap provided at one side with a funnel-like spout, said cap being outwardly flared at its lower end, a broad rubber washer placed against the lower flared end 25 of the cap, means fastening said flared end to said washer, said washer engaging the outer face of the sleeve, and an internally threaded sleeve within the cap and engaging at its lower end the inner face of the rubber 30 washer and being threaded upon the first-mentioned sleeve, substantially as shown and described.

In testimony whereof I hereunto affix my signature.

FRANK J. KROGMANN.
